(57) **CLAIM**

The ornamental design for a push up training equipment, as shown and described.

DESCRIPTION

FIG. 1 is a perspective view of a push up training equipment showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a front elevation view of the push up training equipment where the push up training equipment is shown in a first configuration of use;
FIG. 10 is a front elevation view of the push up training equipment where the push up training equipment is shown in a second configuration of use;
FIG. 11 is a front elevation view of the push up training equipment where the push up training equipment is shown in a third configuration of use;
FIG. 12 is a front elevation view of the push up training equipment where the push up training equipment is shown in a fourth configuration of use;
FIG. 13 is a front elevation view of the push up training equipment where the push up training equipment is shown in a fifth configuration of use;
FIG. 14 is a front elevation view of the push up training equipment where the push up training equipment is shown in a sixth configuration of use;
FIG. 15 is a front elevation view of the push up training equipment where the push up training equipment is shown in a seventh configuration of use;
FIG. 16 is a front elevation view of the push up training equipment shown disassembled; and,
FIG. 17 is an enlarged view of portion 17 shown in FIG. 2. The broken lines in the drawings depict portions of the push up training equipment that form no part of the claimed design.
